(57) CLAIM

We claim, the ornamental design for an audio device with docking station, as shown and described.

DESCRIPTION

FIG. 1 is a front perspective view of an audio device with docking station showing our new design;
FIG. 2 is a front view thereof;
FIG. 3 is a rear view thereof;
FIG. 4 is a side view thereof;
FIG. 5 is another side view thereof;
FIG. 6 is a top plan view thereof;
FIG. 7 is a bottom plan view thereof; and,
FIG. 8 is another front perspective view of the audio device with docking station illustrates an exemplary environment. The broken lines are for environmental purposes only and form no part of the claimed design.
